United States Patent Office

Des. 216,065
Patented Nov. 13, 1968

216,065

TIRE

Brian H. Holmes, Yardley, Birmingham, England, assignor
to The Dunlop Company Limited, Erdington, Birmingham,
England, a British corporation

Filed Mar. 11, 1969, Ser. No. 16,179

Term of patent 14 years

Claims priority, application Great Britain Sept. 19, 1968

Int. Cl. D12—14

U.S. Cl. D90—20

FIG. 1

FIG. 2

FIG. 3

FIG. 4

FIG. 5

FIG. 6

FIGURE 1 is a perspective view of a tire showing my new design, it being understood that the tread and sidewall portions shown in full lines continue throughout the circumference of the tire, and the sidewall not shown is the mirror image of that shown;

FIGURE 2 is a fragmentary perspective view of the tire shown in FIGURE 1;

FIGURE 3 is a fragmentary plan view of the tire shown in FIGURE 1;

FIGURE 4 is a perspective view of a modified form thereof, it being understood that the tread and sidewall portions shown in full lines continue throughout the circumference of the tire, and the sidewall not shown is the mirror image of that shown;

FIGURE 5 is a fragmentary perspective view of the tire shown in FIGURE 4; and

FIGURE 6 is a fragmentary plan view of the tire shown in FIGURE 4.

I claim:

The ornamental design for a tire, as shown and described.
